UNITED STATES PATENT OFFICE.

ISIDOR MENDEL, OF CINCINNATI, OHIO.

DESIGN FOR A TRUNK-TRIMMING.

No. 37,959.

Specification for Design.

Patented April 17, 1906.

Application filed October 30, 1905. Serial No. 285,190. Term of patent 7 years.

To all whom it may concern:

Be it known that I, ISIDOR MENDEL, a citizen of the United States, residing at Cincinnati, Hamilton county, State of Ohio, have invented a certain new, original, and ornamental Design for a Trunk-Trimming, as shown in the accompanying drawing, the figure of which shows the design of the trunk-trimming in perspective view.

I claim as new—

The ornamental design for a trunk-trimming as shown.

ISIDOR MENDEL.

Witnesses:

C. SPENGEL,
C. MEYER.
